UNITED STATES PATENT OFFICE.

FRANK S. LAND, OF KANSAS CITY, MISSOURI, ASSIGNOR TO GRAND COUNCIL ORDER OF DE MOLAY FOR BOYS, OF KANSAS CITY, MISSOURI.

DESIGN FOR A BADGE.

Application filed December 1, 1924. Serial No. 11,550. Term of patent 14 years.

To all whom it may concern:

Be it known that I, FRANK S. LAND, a citizen of the United States, residing at Kansas City, in the county of Jackson and State of Missouri, have invented a new, original, and ornamental Design for a Badge, of which the following is a specification, reference being had to the accompanying drawings, forming part hereof.

In the drawing Fig. 1 is a front view of a badge showing my new design; and Fig. 2 is an edge view of the same.

I claim:

The ornamental design for a badge, as shown.

FRANK S. LAND.
